UNITED STATES PATENT OFFICE.

LAURENCE E. FRENCH, OF SEBASTOPOL, CALIFORNIA.

OIL BURNER.

Application filed June 16, 1923. Serial No. 645,825.

To all whom it may concern:

Be it known that I, LAURENCE E. FRENCH, a citizen of the United States, residing at Sebastopol, county of Sonoma, and State of California, have invented new and useful Improvements in Oil Burners, of which the following is a specification.

This invention relates to a fuel burner and particularly pertains to a low air pressure, stationary head burner for use with liquid fuel.

It is the principal object of this invention to provide a burner head or spray nozzle which is so constructed as to insure that the fuel will be thoroughly atomized as it is delivered to the combustion chamber, without the use of rotary mechanical means for producing centrifugal force effects upon the fuel, and that the mechanical means for agitating, atomizing and delivering the fuel to the fuel jet and throwing it therefrom will be stationary and simple in construction and arrangement so that a blaze of maximum intensity may be obtained in a limited zone, the invention being so constructed as to permit burning structures of various capacities to be readily made from multiple units and assembled in such a compact manner as to allow the burner to be carried from place to place.

The present invention contemplates the use of a stationary nozzle from which vapor is thrown, and which nozzle is disposed in the path of travel of a current of air in such a manner as to utilize a part of the air pressure in discharging a film of oil into the main air current so that the oil becomes finely atomized by a comparatively low air pressure and in a manner to produce a concentrated blaze.

A further object of the invention is to provide an oil burner which will permit the use of two or more fuel nozzles to be located in a single housing for the purpose of increasing the range of capacity of the burner without destroying the proportion of air to atomized fuel necessary for complete combustion.

The invention is illustrated by way of example in the accompanying drawings, in which:

Fig. 1 is a view in longitudinal section through a single unit burner nozzle.

Fig. 2 is a view in section taken on the line A—A of Fig. 1.

Fig. 3 is a view in longitudinal section through a single jet burner nozzle showing

the application of the nozzle to a different form of housing.

Fig. 4 is a view in elevation showing the front end of the same nozzle.

Fig. 5 is a view in elevation showing the rear end of a three jet nozzle.

Fig. 6 is a view in elevation showing the front end of the same nozzle and indicating the position of the three jets in the burner housing.

Fig. 7 is a view in section showing in detail the construction of a single jet nozzle of the same form shown in Fig. 3.

Fig. 8 is a view in section showing the construction of the fuel regulating valve for controlling the fuel jets of a three jet burner as seen on line 8—8 of Fig. 9.

Fig. 9 is an enlarged view in section showing the multiple nozzle as seen on lines 9—9 of Fig. 6.

Referring to the drawings, particularly to Fig. 1 and Fig. 2, 10 indicates a fuel oil pipe adapted to be connected with a suitable source of supply. The oil pipe 10 is held in a central position in the air pipe 11 by means of a perforated disk 12. A tubular air sleeve 13 is mounted on a cylindrical collar 14, the tube being preferably a press fit on the collar. A uniform circular air space 26 is formed between the tube and the collar and a similar air space between the tube 13 and the air pipe 11. Through the collar 14 a number of holes 15 are drilled in such a manner that the air from the air pipe 11 may pass freely therethrough. Upon the end of the collar 14 two concentric circular discs 16 and 17 are mounted and are secured by means of the screw 18 in such manner as to form circular air spaces 19 and 21. The holes 15 pass through the disc 16 but not through the disc 17.

In the collar 14, at a point slightly forward of its center, a series of small radial fuel passageways 22 connect the oil space 24 with the air space 26. A series of horizontal milled grooves 23 connect the air space 26 with the air space 27.

Referring to Figs. 3 and 4, a fuel nozzle 28 is shown as mounted in a housing 29, an oil pipe 10^a enters a fuel preheating chamber 30. An annular air space 27 surrounds the nozzle 28 and is in communication with an air pipe 31. The nozzle 28 is preferably threaded into the burner housing as indicated at 32. The air tube 11 is mounted in a perforated disc 33 which is

supported by a number of bosses 34 in such manner as to leave an air space between the disc 33 and the burner casing. The burner nozzle housing is attached to a sheet metal plate 34 by means of four lugs 35. The sheet metal plate 34 is attached to the door of a furnace in such manner as to close off all the air space except that provided by the annular space 36. This annular air space is formed between the nozzle housing and a hollow circular ring 37. The ring 37 is so constructed as to cause the air entering the furnace by natural draft, through the air space 36 to converge in the direction shown by the arrows 38. At the bottom of the burner casing a drilled passage 39 provides the means of exit for surplus oil. At the bottom of the circular ring 37 an oil pipe 40 is provided for an oil drain.

Referring to Figs. 5 and 6, burner nozzle 29 is shown mounted on annular ring 37 by means of the lugs 35. Three oil burner nozzles or jets 28 are shown in Fig. 6. Three thumb screws 41 are inserted radially in the casing 29 in such manner as to control the flow of oil independently to each of the nozzle jets 28. The lever 42 is attached to a circular oil valve 45 by means of the shaft 43 forming a shut-off valve for two of the nozzle jets 28. The detail of this oil valve is shown in Figs. 8 and 9. It is to be understood that the oil nozzles or jets indicated at 28 in Fig. 6 are similar in construction to the nozzles disclosed in Figs. 1 and 2 of the drawings, in which construction it is apparent that three nozzle streams are created, one indicated by arrow —a— which passes from the end of the nozzle at an outwardly flaring angle, another indicated by the arrow —b— passing substantially parallel to the jet —a—, and a third intersecting stream indicated by the arrow —c—. This peculiar direction given to the various air streams and the manner in which they intersect, are the fundamental features of the present invention, as the first atomization of the air is accomplished by the action of the air streams within the nozzle. This atomization is created in two separate stages, the first taking place within the nozzle shell 13 and the second taking place as the jets emerge from the nozzle to be projected into the furnace.

In the first stage of vaporization, the fuel oil is separated into drops or globules fine enough to be readily carried in suspension with the air passing through the shell 13. This oil is afterwards atomized to a greater degree when the air stream passing through the shell 13 strikes the bevel face of the disks 16 where it will be deflected to pass out in the general direction indicated by the arrow —a— in Fig. 1. This flaring frustoconical jet of air and oil will be acted upon

by the cross current of air passing along the air passageway 19 and in the direction indicated by the arrow —c— in Fig. 1. Another stream of air will be created through the openings 15 and will be deflected outwardly by striking a disk 21, after which this stream will travel in the direction of the arrow —b— indicated in Fig. 1.

In the multiple valve as shown particularly in Fig. 6, three of these nozzles are used and are disposed in a triangular arrangement with an upper nozzle 28 on the vertical center line of the structure and two lower nozzles 28 spaced equidistant therethrough and from each other upon opposite sides of said vertical center line.

By this arrangement, substantially nine air streams are operating in a confined zone to create a composite jet of more intensity and in which large volumes of liquid fuel are atomized and carried forward.

Referring to Fig. 7 a portion of the burner casing is shown at 29^a. The disc 33 is shown mounted on the bosses 34. In this form of nozzle a single disc 44 replaces the two discs 16 and 17 as shown in Figs. 1 and 2. By examination of Fig. 7, it will be seen that the nozzle structure here disclosed is substantially the same as that shown in Fig. 1, in that three air streams are produced as represented by the arrows —a—, —b—, and —c— in both figures, and which streams intersect each other to insure a suitable atomization of the liquid fuel. This is brought about due to the fact that the milled slots 23 permit air to pass directly through the nozzle and against the radial jets 22. This partially atomizes the fuel which enters an enlarged annular space at the forward end of the axle substantially the same as in the structure shown in Fig. 1. The arrow —a— in Fig. 7 indicates the direction pursued by the partially atomized spray as it leaves this space.

While arrow —b— indicates the direction of the intersecting main air stream, an arrow —c— represents the inner air stream.

Referring to Fig. 8 an oil valve 45 is shown mounted in the fuel preheating chamber 30. Three holes 46, 47 and 48 communicate with the three burner nozzles 28 as shown in Fig. 6. By comparison of Figs. 6 and 8, it is to be understood that the position of the regulating ports 46, 47, and 48 is exactly reversed in the two views, and that the port 46 in Fig. 8 is intended to assume an operative position relative to the right hand lower nozzle in Fig. 6. The oil valve 45 is connected to lever 42 shown in Fig. 5 by means of the shaft 43. The amount of motion of the valve 45 is limited by the set screw 49 acting in the slot 50. The holes 46, 47 and 48 are drilled in the burner casing 29. The openings in the valve 45 are

elongated slots at the points 51 and 52 and a circular hole at the point 48. The slot 51 is equal in length to three round holes 46. The slot 52 is equal in length to two round holes 47.

In the operation of the present invention, the air under pressure from a suitable blower enters the air space 27 and is communicated to all the various air passages at the rear 10 of the nozzle. At this point the air stream divides into three distinct paths, the quantity of air flowing through each port being controlled by the relative areas of the ports.

The largest air stream issues in the form of a circular jet from the space formed between the tube 13 and the housing 11 as indicated by the arrow at 20. A second air stream passes through the holes 15 into the annular space formed between the discs 16 and 17 20 and issues in a circular jet as indicated by the arrow at 21. The intersection of these two air jets has an important bearing upon the action of the device which will be explained later. A third air stream passes through the milled slots 23 being concentrated upon the fuel issuing from the fuel passageways 22. The air streams passing through the various milled slots 23, are 25 equalized upon entering the small annular space formed between the tube 13 and the collar 14, and issue in the form of a circular jet as shown by the arrow at 19. In the form of jet shown in Fig. 7 the action is identical but the construction is slightly different. Air pressure enters the annular space 26 through milled slots indicated by the dotted lines, the sleeve 14 forming closed air passages of these milled slots, and they 30 perform the same function as the drilled holes 15 shown in Figs. 1 and 2.

Fuel oil under pressure from a suitable source enters the oil pipe 10 and fills the oil space 24 and in Fig. 3 the preheating reservoir 30 in the burner housing. The oil entering this reservoir is brought in contact with a considerable surface of the burner casing. This not only acts as a preheater for the incoming fuel oil but acts as a cooling agent for the burner housing. The viscosity of the fuel is thus reduced which promotes finer atomization. At the same time the burner housing and nozzle jets are cooled to a point where they are unaffected by the heat from the oil flame in the furnace. The oil issues under pressure in the form of small jets through the small passageways 22. Owing to the restricted size of the passageways the fuel issues with equal force from each jet. As the oil issues in jets from the holes 22, it is confined in a narrow annular space and is there immediately acted upon by individual air jets issuing from the milled slots 23. In this way the oil is 45 partially atomized within the burner nozzle itself before being projected into the furnace. This feature of the construction has an important bearing upon the low air pressure required for complete atomization of fuel in this nozzle. Both the inner and outer surfaces of the annular passage 26 are coated however with a film of oil due to the force of surface adhesion. The oil which has been atomized is carried forward by the air stream and issues from the circular slot 50 in the direction of the arrow —a—. The two oil films clinging to the inner and outer surfaces of the annular space 26 are driven forward along these surfaces until they reach the extreme forward edge of each respective surface. The oil film clinging to the inner surface of the tube 13, when it reaches the pointed tip of that tube, is there placed at the intersection of two air streams, 55 indicated by arrows —a— and —c—. The oil film passing along the surface of the core 14, spreads itself over that surface in a thin uniform film due to the intersections of the oil jets issuing from the various passageways 22, and is driven forward by the air stream and held against the surface of the core by the force of adhesion. This thin film of oil spreads itself uniformly over the inner surface of the disk 16, and reaches the 60 extreme forward tip of that disk in the form of a thin evenly spaced film. It is there placed at the intersection of two air jets indicated by arrows —b— and —c—. It will thus be noted that by the use of three 65 annular air streams each film of oil, which is held in contact with a nozzle surface, is placed at the intersection of two air streams. The intersection of these air streams acting upon a thin film of oil at the points mentioned results in tearing away the oil from 70 these surfaces in the form of extremely small particles, the air acting against the force of adhesion in such manner as to prevent the oil film from being rolled over the 75 projecting corner which results where a single air stream is used under a comparatively low pressure. The air stream indicated by arrow —c—, being somewhat larger than the others, causes the resultant flow of air and 80 atomized oil to be concentrated in a forward direction without undue spread, thus causing a blaze of maximum intensity and high temperature which is necessary for the complete vaporization of the atomized fuel. In 85 the construction shown in Fig. 7, the atomized fuel and air actually converge at a focus at a slight distance in front of the nozzle. The auxiliary air entering the ring 37 90 as shown by the arrows 38 in Fig. 3 assists 95 this converging action.

Another important action which results from the construction shown is the partial vacuum which is caused in the oil passageways 22 by the air jets blowing across the 100

oil openings at right angles thereto. The partial vacuum caused by this action makes it possible to use a lower oil pressure than would otherwise be necessary.

5 The amount of opening at the point 19 may be adjusted by forcing the tube 13 forward or backward with relation to the core 14, thus varying the amount of air issuing from this port. The air spaces and oil passages are rendered accessible for cleaning purposes by removing the screw 18 and the discs 16, 17 and in Fig. 7 the disc 44.

10 In the construction shown in Fig. 3, in the event of any oil entering the air space 27, due to shutting off the air pressure without simultaneously closing off the oil supply, the oil entering the air space 27 is automatically drained off through the drilled port 39. Any oil overflowing the outer surface 20 of the nozzle housing is also carried by gravity to the lowest point of the housing and in both cases this oil drips into the space formed by the ring 37 and is drained off by the oil drain pipe 40 which can, if required, be connected to an automatic oil shut off mechanism (not shown) which may be attached to the oil supply pipe 10.

15 Referring to Figs. 5, 6 and 8, the action of the three jet nozzle is as follows. The proportion of oil entering each nozzle 28 is independently adjusted to suit the air supply by means of the three thumb screws 41. The fuel entering each jet 28 is adjusted by means of its corresponding thumb screw until a clear blaze of maximum intensity is obtained. The oil control valve shown in Figs. 8 and 9 makes it possible to operate either one, two or three jets by means of a slight motion of the lever 42. 20 The oil valve 45 operates in the following manner. In the position shown all three jets are in operation as the holes in the valve 45 register with the corresponding holes in the casing shown at 46, 47 and 48. 25 When the lever 42 is moved slightly to the left the valve 45 is moved also, until the hole 48 in the valve no longer registers with the corresponding hole in the casing thus closing off jet Number 3. The slot 52, however, still registers with the hole 47 thus leaving jets Numbers 1 and 2 in operation. When the lever 42 is moved to the extreme left so that the set screw 49 registers with the opposite end of slot 50, the slot 52 no longer registers with the hole 47, thus closing the action of jet No. 2, but as the slot 51 still registers with the hole 46 jet No. 1 remains in operation. It is thus impossible to shut off the burner entirely by 30 means of the lever 42. This lever, however, controls the capacity of the burner, increasing that capacity three times the minimum. The lever 42 can thus be connected by suitable means to a control mechanism in another part of the building, and the capacity

of the burner regulated by hand through a large range without danger of extinguishing the blaze. The lever 42 may also be connected to a suitable thermostatic control mechanism which will vary the size of the 70 flame in the burner without danger of extinguishing it, thus eliminating the necessity of a pilot light.

It will thus be seen that by the use of the oil burner here disclosed, it is possible 75 to operate one or more burner jets in a single burner housing by means of a low air pressure and a low oil pressure, which insures the minimum power requirements.

80 While I have shown the preferred form of my invention as now known to me, it will be understood that various changes might be made in the combination, construction, and arrangement of parts by those skilled in the art without departing from the spirit 85 of the invention as claimed.

Having thus described my invention, what I claim and desire to secure by Letters Patent is:—

1. In a liquid fuel nozzle to which air 90 and a liquid fuel way be delivered under pressure, means therein for dividing the air passing therethrough into substantially three concentric columns, to the intermediate one of which said liquid fuel is delivered, and means for thereafter co-mingling the air streams in said columns to create atomization of the liquid fuel.

2. A liquid fuel burner to which air and liquid fuel may be delivered under low 100 pressure, a plurality of parallel passageways in the burner, an annular passageway circumscribing said parallel passageways, said passageways being so formed that air delivered thereto will be discharged from 105 the burner in columns intersecting the mouth of the burner, a fuel chamber in the burner, a plurality of intermediate air passageways formed through the burner and in communication with the oil chamber whereby 110 air discharging through said intermediate passageways will draw oil from the chamber, atomize it and deliver it to the vortex of the air columns intersecting the mouth of the burner.

115 3. A low pressure liquid fuel nozzle having means for forming a plurality of relatively small parallel air columns, a circumscribing annular air column flowing parallel thereto, means for causing the small columns to intersect the annular column at the mouth of the nozzle, a plurality of intermediate air columns, oil supply means, and means whereby the intermediate air columns will atomize the oil and deliver it in an annular jet to the vortex of the intersecting air columns.

120 4. A low pressure liquid fuel burner comprising a tubular casing, a nozzle mounted therein in a manner forming an annular air 125

passageway therebetween, a plurality of relatively small air passageways formed longitudinally through the nozzle, a plurality of intermediate air passageways formed 5 through the nozzle, an oil chamber formed in the nozzle and in communication with said intermediate passageways, and deflecting means at the end of the nozzle causing columns of air discharging through the annular passageway and the small passageways to intersect at the end of the burner and to cause columns of air passing through 10 the intermediate passageways and drawing oil from the oil chamber to atomize the oil 15 and deliver it to the vortex of said intersecting air columns.

5. A low pressure liquid fuel burner comprising a tubular casing to which air may be delivered, an oil delivery pipe disposed 20 in the casing, a burner nozzle disposed concentrically in the end of the casing and connected to said pipe, an oil chamber in said nozzle in communication with said oil pipe, the nozzle being smaller in diameter than 25 the interior of the casing whereby to form an annular air passageway therebetween, a plurality of relatively small parallel air passageways formed through the nozzle, a plurality of intermediate passageways formed 30 through the nozzle, radial oil passageways connecting the intermediate air passageways with the oil chamber, and stationary deflecting means at the end of the nozzle adapted to cause columns of air discharging through 35 the annular passageway and the small passageways to intersect at the mouth of the burner, and to cause columns of air passing through the intermediate passageways and drawing oil from the oil chamber to atomize 40 the oil and deliver it to the vortex of the intersecting air columns.

6. In a liquid fuel nozzle to which air and oil are delivered under pressure, means for dividing the air passing through the 45 nozzle into three substantially parallel streams, means for delivering oil to the intermediate stream whereby partial atomization of the oil will be brought about by the action of said intermediate stream within 50 the nozzle, and means for subjecting the intermediate stream and the atomized oil carried thereby to the further atomization action of the two other air streams by their intersection with the intermediate stream.

55. 7. In a liquid fuel nozzle to which air and oil are delivered under pressure, means for dividing the air passing through the nozzle into three substantially parallel streams, means for delivering oil to the intermediate 60 stream whereby partial atomization of the oil will be brought about by the action of said intermediate stream within the nozzle, and means for subjecting the intermediate

stream and the atomized oil carried thereby to the further atomization action of the 65 two other air streams by their intersection with the intermediate stream and with each other.

8. In a liquid fuel nozzle to which air and oil are delivered under pressure, means for dividing the air into three concentric columns, means for delivering oil to the intermediate column whereby its partial atomization will take place within the nozzle, and means for projecting said intermediate oil-laden column of air in the vortex created by the intersection of the outer and inner air columns whereby further atomization will be effected.

9. In a liquid fuel nozzle to which air and oil are delivered under pressure, means within the nozzle for creating a pair of concentric air columns adapted to intersect each other when said columns are projected from the nozzle tip, and a plurality of separate intermediate columns adapted to be projected into the vortex of intersection of said first named air column, and means for projecting the oil into said nozzle across said separate intermediate columns whereby partial atomization of the oil and the air in said intermediate column will be brought about within the nozzle, after which further atomization will be effected when said intermediate columns of air are projected into the vortex of intersection of the concentric air columns.

10. A liquid fuel burner comprising a plate upon which a plurality of fuel nozzles are mounted and through which plate ports are formed to deliver oil to the individual nozzles, an oil chamber on the back of said plate for delivering oil to all of said ports, and a rotary disk disposed within the chamber and on the back of the plate, said disk being formed of ports adapted to be moved to register with the ports in the plate and to thus simultaneously regulate the supply of oil to the nozzles.

11. A liquid fuel burner comprising a plate upon which a plurality of fuel nozzles are mounted and through which plate ports are formed to deliver oil to the individual nozzles, an oil chamber on the back of said plate for delivering oil to all of said ports, a rotary disk disposed within the chamber and on the back of the plate, said disk being formed of ports adapted to be moved to register with the ports in the plate and to thus simultaneously regulate the supply of oil to the nozzles, said ports in the disks varying in arcuate length, whereby oil may be admitted to one or more of the nozzles and may be simultaneously regulated to permit equal quantities.

LAURENCE E. FRENCH.
